UNITED STATES PATENT OFFICE.

ALBERT T. SNEDEN, OF CLOSTER, NEW JERSEY.

DESIGN FOR AN INSECTICIDE OR OTHER BOX.

46,755.

Specification for Design.

Patented Dec. 8, 1914.

Application filed June 27, 1914. Serial No. 847,761. Term of patent 14 years.

To all whom it may concern:

Be it known that I, ALBERT T. SNEDEN, a citizen of the United States, residing in Closter, in the county of Bergen and State of New Jersey, have invented a new, original, and ornamental Design for Insecticide or other Boxes, of which the following is a specification, reference being made to the accompanying drawing, forming part thereof.

In the drawing, Figure 1 is a top or plan view of a box showing my new design. Fig. 2 is an edge view thereof.

Copies of this patent may be obtained for five cents each, by addressing the "Commissioner of Patents, Washington, D. C."

I claim:

The ornamental design for an insecticide or other box, as shown.

In witness whereof, I have hereunto signed my name in the presence of two subscribing witnesses.

ALBERT T. SNEDEN.
